[57] CLAIM

The ornamental design for a fixture hanger, as shown and described.

DESCRIPTION

FIG. 1 is a perspective view of fixture hanger, showing my new design;

FIG. 2 is a side elevational view thereof as taken along the line 2—2 in FIG. 5;

FIG. 3 is a side elevational view thereof taken from the opposite side shown in FIG. 2;

FIG. 4 is a rear elevational view thereof as taken along the line 4—4 in FIG. 6;

FIG. 5 is a front elevational view thereof as taken along the line 5—5 in FIG. 6;

FIG. 6 is a top plan view thereof; and

FIG. 7 is a bottom plan view thereof, as taken along the lines 7—7 in FIG. 4.

FIG.1

FIG.2

FIG.3

FIG. 4

FIG. 5
